CRAWLER TRACTOR LOADER

Herbert W. Borer, Naperville, and Max E. Butterfield
and Barry L. Zauss, Peoria, Ill., assignors to Caterpillar
Tractor Co., Peoria, Ill., a corporation of California

Filed Sept. 22, 1966, Ser. No. 3,958

Term of patent 14 years

(Cl. D14—3)

E19 - 3

E19 - 4

FIG. 1 is a right side elevational view of a crawler tractor loader embodying our new design;

FIG. 2 is a left side elevational view of the same;

FIG. 3 is a view in front elevation of the same;

FIG. 4 is a view in rear elevation of the same; and

FIG. 5 is a plan view of the same.

The essential features of our design reside in those portions shown in full lines.

We claim:

The ornamental design for a crawler tractor loader, substantially as shown and described.
